UNITED STATES PATENT OFFICE.

JOHN ROGERS, OF NEW CANAAN, CONNECTICUT.

DESIGN FOR A GROUP OF STATUARY.

SPECIFICATION forming part of Design No. 13,392, dated October 31, 1882.

Application filed October 2, 1882. Term of patent 14 years.

To all whom it may concern:

Be it known that I, JOHN ROGERS, a citizen of the United States, residing at New Canaan, in the county of Fairfield and State of Connecticut, have invented and produced a new and original Design for a Group of Statuary, of which the following is a specification, reference being had to the accompanying photographic illustration, forming part thereof.

10 The design is taken from Shakespeare's play of "Othello;" and it consists of four figures—Othello, Desdemona, Iago, and Cassio—and is in illustration of the remark that Iago makes when he sees Desdemona and Cassio together, 15 "Ha! I like not that!" This line is put on the base of the group. Cassio has Desdemona's hand in his, and bows his head in the act of taking leave of her, while she advances to meet Othello, whom she hears approaching on the other side of a vase which is seen in the center 20 on top of a part of a garden-wall. Othello has an open letter in his hand, and glances off from it to Iago at his right, who is leaning forward and watching Desdemona and Cassio together as he makes the exclamation seen on the base 25 of the group.

I claim and desire to secure by Letters Patent—

The design for a group of statuary, consisting of four figures representing Othello, Desdemona, Iago, and Cassio, in illustration of the line in Shakespeare's play of Othello "Ha! I like not that!" which is printed on the base.

JOHN ROGERS.
